Charles G. Bauer,
INVENTOR
BY Victor J. Evans

J. W. E. /
WITNESS:

ATTORNEY

UNITED STATES PATENT OFFICE.

CHARLES G. BAUER, OF BROOKLYN, NEW YORK, ASSIGNOR TO OLIVER C. SAFIR, OF NEW YORK, N. Y.

KNITTING-MACHINE HEAD.

Application filed July 17, 1920. Serial No. 396,913.

To all whom it may concern:

Be it known that I, CHARLES G. BAUER, a citizen of the United States, residing at Brooklyn, in the county of Kings and State 5 of New York, have invented new and useful Improvements in Knitting-Machine Heads, of which the following is a specification.

This invention relates to knitting machines and has particular reference to the 10 needle mechanism and needle operating mechanism therefor.

One of the principal objects is to provide a reciprocatory holder for each of the needles.

15 Another object is to provide a large bearing surface for the holders.

Another object is to provide each of the holders with anti-friction means for effecting reciprocation.

20 Still another object is to provide an improved cam mechanism.

Other objects will appear from the following description and claim.

All of these objects are accomplished by 25 mechanism shown in the accompanying drawing consisting of one sheet, in which:—

Figure 1 is a front elevational view of my improved knitting machine.

Figure 2 is a horizontal sectional view 30 taken substantially in line 2—2, Figure 1.

Figure 3 is a horizontal sectional view taken substantially in line 3—3, Figure 2.

Figures 4 and 5 are detail views of the cam device.

35 Figure 6 is a detail view of the core. Like characters of reference refer to like parts throughout.

Needles for knitting machines have been formed with a lug which has been operated 40 on directly by a cam mechanism, and this constant wear on so delicate a part as the lugs of the needles necessarily are, has resulted in constant breaking of the needles and considerable loss not alone in the cost

45 of the needles themselves, but also in the amount of time required for replacing the needle and the enforced idleness of the machine during such replacing. The present invention contemplates providing needle

holders for the needles so that the cams no longer work directly on the needles. Each holder is provided with an anti-friction roller working in the cam slot, and all of the

50 holders are mounted in a frame which provides large bearing surfaces for the holders.

Incidentally the arrangement has provided that the cam would have a greater diameter so that the inclines have not had to be placed at so steep an angle.

In the accompanying drawing the improvement has been shown as applied to the knitting machine used for making shoe laces, in which it is particularly useful, but it is to be understood that the invention is equally applicable to all kinds of knitting machines.

Referring more particularly to the drawings, 1 and 2 represent two rods of the supporting frame-work of the machines, and 3 is a supporting frame member which may 70 be mounted on said rods as shown. This frame-work may, however, be of any suitable form to support the structure herein-after described.

A shell member 4 is rising from the supporting frame-member and being provided on its interior with a pair of co-acting cam members 5 and 6 which may be secured in place in said shell 4 by being sweated or welded thereto or in any other well-known 80 manner. The exterior of the shell is provided with a supporting flange 7 and a flange 8 which together define between them a belt-race 9 for the driving belt. The belt race is provided with converging walls 85

which meet midway between the flanges, as clearly shown in Figure 1 of the drawings. The cam members 5 and 6 are spaced apart at their cam ends to form a cam groove 10. A bearing sleeve or core 11 is provided 90

with a plurality of longitudinally disposed slots 12 in its upper end and in each of these slots is seated a needle holder 13 having an anti-friction roller 14 on its outer edge, the anti-friction rollers of all of the 95 holders 13 being positioned in the cam slot 10. Seated in each of the holders 13 near inner faces thereof is a needle 15 of the usual type, the nib or lug 16 of which is utilized for preventing turning of the needle 100 in its holder. A tube 17 is threadedly secured in the lower end of the core 11 and extends upwardly therethrough, co-operating with the inner faces of the needle holders to confine the needles in the holders and 105 in their circular vertical arrangement. The knitted fabric is drawn down through the tube 17 by any desired means and the tube 17 may be adjusted vertically to loosen or tighten the stitch.

In operation, the shell 4 and the cam members 5 and 6 are rotated, whereby the cam-slot 10 causes rollers 14 to move up and down thereby reciprocating the needle holders and needles to effect the knitting operation.

While I have described what I consider to be the most desirable embodiment of my invention, it is obvious that many of the details may be varied without in any way departing from the spirit of my invention; and I therefore, do not limit myself to the exact details of construction herein set forth nor to anything less than the whole of my invention limited only by the appended claim.

What I claim as new and desire to secure by Letters Patent is:—

A circular knitting machine of the char-

acter described comprising a supporting frame, a bearing sleeve rising from the frame and provided with a plurality of vertically disposed slots formed in the portion thereabove, a tube threadedly secured centrally in the lower portion of the bearing sleeve, a shell rising from the frame and supporting the sleeve, a pair of superposed members arranged between the shell and sleeve and having a pair of cammed operating surfaces to provide a cammed groove, a needle holder mounted in each slot, a roller carried by each holder and operating within the groove and needle secured to the inner sides of the needle holder and arranged in spaced relation around the tube.

In testimony whereof I have affixed my signature.

CHARLES G. BAUER.
